UNITED STATES PATENT OFFICE.

AUGUST H. DEIKE, DECEASED, LATE OF TAKOMA PARK, MARYLAND, BY MILDRED DEIKE, ADMINISTRATRIX, OF TAKOMA PARK, MARYLAND, ASSIGNOR TO TAKOMA MANUFACTURING COMPANY, OF TAKOMA PARK, MARYLAND, A CORPORATION OF MARYLAND.

WATER-CLOSET.

Application filed February 3, 1927. Serial No. 165,713.

This invention relates to water closets and more particularly to automatically operating ventilated closets.

It is a general object of this invention to provide a novel and improved type of automatically operated ventilating closet.

More particularly the objects are to provide a closet of the type specified in which the flow of water to the flushing tank is controlled by the position of the cover of the bowl; to provide a flushing valve which is a tubular extension of the pipe connecting the tank and bowl and has means for its positive operation by the movement of the bowl cover or lid; to provide simple and positive means for operating the flushing valve and the valve controlling the water supply to the tank; to provide improvements in structure of the type described so that a minimum number of simple parts are used and in general to provide improvements in the closet disclosed in Patent No. 1,286,249 December 3, 1918.

Other and further objects will be more apparent from a consideration of the accompanying drawings and following specification wherein is disclosed a single exemplary embodiment of the invention, with the understanding, however, that various changes may be made therein such as fall within the scope of the appended claims without departing from the spirit of the invention.

In said drawings;

Figure 1 is a side elevation of a water closet showing the flush tank in vertical section.

Figure 2 is a plan view with the cover of the tank removed.

Figure 3 is a transverse vertical section of the tank, certain parts being broken away, and

Figure 4 is a horizontal section on line 4-4 of Figure 1.

In the aforementioned patent is shown a water closet in which the water flowing into the tank produces an aspirator action to ventilate the bowl through the flushing pipe and tubular flushing valve, provision being made to automatically flush the bowl after use and to leave the tank empty until the closet is again used. During use water flows continuously into the tank to produce the aforementioned aspirator action. The pres-

ent invention incorporates all of these features and provides improved apparatus for carrying them into effect.

Referring to the drawings there is shown at 10 a closet bowl which may be of the usual type and a flushing tank 11 located above and behind the bowl and connected thereto by a single short flushing pipe 12 which leads from the bottom of the tank to the back of the bowl near the top thereof. The bowl is provided with the usual seat and the lid or cover 14. The seat and lid are hinged to the cross bar 15 supported from the bowl.

The tank 11 is provided with a cover 16 which makes it substantially airtight. A fore and aft partition 17 separates one end of the tank into what may be termed a separator 18. An air vent 19, preferably leading to a stack, is provided near the top of the separator 18. An opening 20 at the bottom of the partition allows water to run from the separator to the main portion of the tank. A tube 21 passes through the partition near the normal water line of the tank and the inner end is preferably secured to the end wall of the tank as at 22, an opening 23 in the tube being directed downwardly.

The water supply pipe 24 is secured to a bushing 25 preferably secured in the bottom of the tank by a nut 26, suitable packing 27 being used to make the joint watertight. A tubular extension 27 is threaded into the bushing and is provided with the cap 28. A nozzle 29 projects laterally from the cap so that a stream therefrom will pass through the tube 21 and into the separator. The supply of water to the nozzle is controlled by the valve disc 30 which cooperates with a seat 31 on the lower end of the extension 27. The valve disc is secured, by the nut 32, to the lower end of a valve stem 33. This stem extends beyond the upper end of the cap 28 and is suitably yoked as shown at 34. A guide 35 is secured in the end of the cap 28 and packing 36 is compressed around the stem 33 by the nut 37. Depression of the valve stem allows water to flow through the nozzle 29.

The flushing valve comprises a tubular member 38 movable vertically into and out of contact with a seat 39 formed on the

bushing 40 passing through the bottom of the tank and held in position by the nut 41, suitable packing being interposed to prevent leakage. The flushing pipe 12 is attached 5 to the lower end of the bushing. When the tubular member is seated on 39 it forms an extension of the flushing pipe which reaches up into the tank. The upper end of the member 38 is open to form an overflow for 10 water. Before the water reaches such level however, the tube 38 acts as a ventilator for bowl. Water flowing from the nozzle 29 and passing into the tube 21 causes an aspirating action tending to draw air out of 15 the main portion of the tank. The only means of ingress to this portion of the tank is through the flushing pipe and tube 38. This maintains a circulation of air and gases 20 from the bowl into the tank and then into the separator where they pass off through the vent. Such action continues substantially as long as water is flowing from the nozzle 29. The water is separated from the air and gases in the separator 18 and the 25 water flows through the passage 20 into the main portion of the tank to fill the same to the level of the top of the tube 38. If this tube be lifted to the position shown in Figure 3 the water is discharged through the 30 flushing pipe to the bowl in the usual manner.

A pair of guide rods 42 are secured to the bottom of the tank and extend upwardly 35 beside the tube 38 which is provided with guides 43 to cooperate therewith to insure proper seating. The upper end of the tube 38 is guided in a suitable aperture in the plate 44 which is bolted to the ends of the guide rods 42 and has a tight fit around the 40 extension 27. The opposite end of the plate 44 is supported by the tube 45 which passes through the bottom of the tank and is secured thereto by the collar 46 and nut 47 with suitable interposed packing to prevent 45 leakage. An operating rod 48 passes through the tube 45 and has the top end formed with an eye 49. The lower end of the rod extends below the tube and tank and is adapted to be moved by means to be 50 later described.

In order to operate the supply and flushing valves, one of which is always open while the other is closed the following linkage is used. A lever 50 is pivoted at 51 in 55 a bearing member 52 supported on the plate 44. One end of the lever passes through the eye 49 so that movement of the operating rod 48 causes the lever to rock about its pivot. A second lever 53 has its bifurcated 60 end 54 bearing on the stud 55 mounted in the partition 17. The inner end of the lever 53 is over the inner end of the lever 50 and these ends are connected by the link 56.

A chain 57 is connected to a cross rod 58 65 in the tube 38 and its upper end is secured

to the lever 50 at 59. Thus a downward movement of the rod 48 lifts the tube 38 to cause flushing of the bowl.

The yoke 34 on the valve stem 33 straddles and is pivoted to the intermediate portion 70 of the lever 53 so that downward movement of the rod 48 closes the valve 30 against its seat where it will be tightly held by water pressure.

A rock shaft 60 shown best in Figure 4 75 is journaled in the bearings 61 and 62, secured to the bottom of the tank. An arm 63 projects at right angles to the shaft 60 and passes through the eye 64 in the attachment 65 adjustably secured to the rod 48. 80 A second arm 66 extends from the shaft 60 at the opposite end thereof and in a direction toward the bowl.

On the hinge rod 15 of the bowl are arranged two arms 67 having the bent inner 85 ends which are bifurcated as at 68 to engage over the hinge members 69 of the lid or cover 14 so that movement of the lid is imparted to the arms. The back ends of the arms 67 are rigidly connected together by 90 the bar 70 which passes at right angles through a hole in the tube 71 which has a snug sliding fit over the arm 66. Upon examination of Figure 1 it will be seen that lifting the lid will depress the bar 70 and 95 raise the arm 63 which will push upon the rod 48 lower the tube 38 and open the valve 30.

The lid must be lifted to make use of the 100 closet and in so doing the flush valve is closed and water turned on, which, as before explained, starts to fill the tank and causes ventilation of the bowl by aspirator action. This action continues as long as the lid is lifted. When the lid is returned to 105 its closed position the tube 38 is lifted and allows the bowl to be flushed by the water accumulated in the tank. At the same time the supply of water is shut off and the tank remains empty until the lid is again lifted. 110

Having thus described my invention, what is claimed and desired to be secured by Letters Patent is:

1. In a ventilating closet construction, in combination, a substantially air-tight tank 115 having a gas outlet, a bowl, a lid therefor, a single pipe connecting the tank and bowl, means for effecting a discharge of gas from said tank, a flushing valve for said pipe having a passage therethrough forming an extension of the pipe whereby the flushing valve acts as an overflow and ventilating means and means to lift said valve when said lid is closed.

2. In a ventilating closet construction, in combination, a substantially air-tight tank, 125 a bowl having a hinged lid, a single pipe connecting the tank and bowl, means for effecting a discharge of gas from said tank, a flushing valve for said pipe comprising 130

a tubular member adapted to form an extension of said pipe and means operated by movement of said lid to lift said valve from said pipe.

5 3. In a ventilating water closet construction, the combination of a bowl having a hinged lid and seat, a flushing tank, a flushing pipe connecting said tank and bowl, a flushing valve controlling the flow through 10 said pipe, ventilating means for the closet operated by water supplied to the tank, and means operated by lifting of said lid to close said valve and start the flow of water to the tank.

15 4. In a ventilating water closet construction, a substantially gas-tight flushing tank, a bowl, a lid, a pipe connecting the tank and bowl, means for effecting a discharge of gases from said tank, a flushing valve controlling said pipe formed with a passage for air and gases and means operated by movement of said lid to actuate said valve.

20 5. In a ventilating water closet construction, in combination, a substantially gas-tight flushing tank, a bowl, a single pipe connecting the tank and bowl, a tubular member extending above the normal level of water in said tank and movable to open and close said pipe said member being formed 25 with a passage for air and gases, a water supply pipe connected to the tank, an extension thereof within said tank and having a nozzle, a valve to control the flow of water to said nozzle and means connecting said

30 valve and tubular member whereby movement of one is always dependent upon movement of the other.

6. In a ventilating water closet construction, in combination, a substantially gas-tight flushing tank, a bowl, a lid thereon, a pipe connecting the tank and bowl, a tubular member extending above the normal level of water in said tank and movable to open and close said pipe, a water supply pipe connected to the tank, an extension 40 thereof within said tank and having a nozzle, a valve to control the flow of water to said nozzle, means connecting said valve and tubular member for simultaneous movement and means dependent upon the movement of 45 said lid to actuate one of said connected parts.

7. A ventilating water closet including in combination, a bowl having a hinged lid, a substantially air-tight tank having a partition therein forming a portion of the tank into a separator, a gas outlet near the top of said separator, a passage for water beneath said partition, a tube passing through said partition, a nozzle in the main portion 55 of said tank directed toward the opening in said tube, a supply pipe for said nozzle, a valve therein, a pipe connecting the bottom of said tank to said bowl, a tubular valve adapted to seat on the end of said pipe 60 and form an extension thereof, a system of levers connecting said valves and said lid whereby movement of said lid serves to actuate both valves.

In testimony whereof I hereunto affix my 70 signature.
